SCALE USED FOR RADIO APPARATUS OR
THE LIKEHans Strassenburg, Berlin, Germany, assignor to
Radioaktiengesellschaft D. S. Loewe, Berlin-
Steglitz, Germany, a company of GermanyApplication January 27, 1938, Serial No. 187,186
In Germany January 30, 1937

15 Claims. (Cl. 116—124.1)

This invention relates to tuning scales for radio apparatus, and more particularly to scales of that type which bear the names of a large number of stations and the name of the tuned-in station is caused to be illuminated, and it is the object of the invention to improve generally on tuning scales of this character.

In the past it has been usual to employ either vertical scales, in which the name of the tuned-in station is illuminated by a strip of light caused to move over the entire width of the scale, or scales in which the names of the stations are divided into columns and the entire scale, including all station names, is lighted from the rear, tuning in being performed by the adjustment of an indicator to a graduation against the name of the desired station.

These arrangements have the disadvantage that the names of the stations require to be disposed in accordance with the calibrations, so that it is impossible to arrange the station names symmetrically or evenly, and irregularities occur in the disposal of the names.

This disadvantage is avoided by the tuning scale according to the invention, which is distinguished by its very convenient and lucid form.

The invention will now be described more fully with reference to the accompanying drawing, in which

Fig. 1 is a rear diagrammatic view of the tuning scale.

Fig. 2 is a vertical sectional elevation on the line 2—2 of Fig. 1.

Fig. 3 shows a partial rear view of the tuning scale with the casing 10.

In the drawing, 8 is the scale plate bearing the names of the stations and the wavelength calibrations w. This plate is illuminated from the rear by one or more suitable light sources provided on the slide s.

The essential feature of the arrangement consists in the casing 10, which is mounted firmly behind the scale plate and is divided by light-screening partitions 9 into single compartments k₁, k₂, k₃, etc. These compartments are arranged in accordance with the single lines of the station names. The casing 10 having the light-screening partitions is also furnished in the rear wall with openings L, through which the light from the slide s is enabled to enter the single compartments k₁, k₂, k₃, etc., and illuminate the particular station names from the rear. The openings L are stamped into the wall of the casing to agree with the wavelength calibrations, and upon actuation of the tuning knob

1 the slide s carrying the light source, guided by the rails 5 and 6, is moved past the openings L by the cord drive 2, 3, 4. In a certain position of the tuning knob 1 or tuning condenser A the slide s is located behind a certain opening L, so that the name of the station corresponding to the particular tuning adjustment is caused to be illuminated.

The directional effect on the light produced by the openings L is such that merely one station name, which if desired can also be furnished with a special marking, is illuminated. The next station name above or below is screened off by the partitions 9, and the station names to either side are so spaced that they cannot be reached by the cone of light produced by the opening L.

If desired, the single horizontal compartments k₁, k₂, k₃, etc., formed by the partitions 9 can also be divided by transverse partitions in the vertical direction in order essentially to preclude the least possibility of several station names located in the horizontal direction being illuminated simultaneously. These vertical partitions may be seen from Fig. 3, wherein a partial rear view of the casing 10 is schematically shown. 20 19 are the horizontal partitions and 11 are the vertical partitions. Generally speaking, however, the spacial disposal of the names horizontally and also the directional effect on the light will be such that even without the transverse 25 partitions only one name will be illuminated at any given time.

Fig. 2 shows the scale 8 with the casing 10, the single compartments k₁, k₂, k₃, etc., the openings L and the slide s.

Conveniently the slide s can be made, for example, cylindrical along the middle portion and can be furnished towards the scale with a narrow slot, through which the light is projected on to the openings in the wall of the casing 10. It 40 can be furnished with a lining of reflecting material (which may be sprayed on), and if desired the slot can be covered with a light-transmitting material in order to obtain a diffuse light and accordingly an even illumination of the station names. There can also be provided at the upper and lower ends of the slide s a prism 7 (Figs. 1 and 2), which permits of illuminated indication on the scale, not only of the station name, but also of the appertaining wavelength. 45

The light-screening partitions 9 within the casing 10 will preferably be made of a good reflecting material, such as sheet metal having a bright surface, or also of a non-metallic material, such as cardboard or a pressed material, 50

which if desired can be furnished with a reflecting coating, for example by a spraying process.

An essential advantage associated with the tuning scale according to the invention consists in the fact that the station names can be disposed perfectly symmetrically and in pleasing arrangement on the scale, and that consideration does not require to be paid to the calibrations. The calibrations call for consideration upon the production of the openings L, which is considerably more simple to perform.

In the embodiment illustrated in the drawing the upper light compartments k_1, k_2, k_3 , etc., are for stations operating on medium waves, and the lower compartments are for long-wave stations. Provision can naturally also be made for the names of short-wave stations. The station names in the single wave ranges can accordingly be arranged in very convenient and lucid form.

It will be obvious that no limitation is made to the specific embodiment shown in the drawing, and that numerous modifications are quite possible within the meaning of the above description and the appended claims without departing from the spirit of the invention. Thus, for example, the slide s carrying the light source can be arranged obliquely, and the openings L can then be disposed vertically one below the other. The effect is the same. The station names then naturally also require to be disposed vertically on the scale.

What I claim as new and desire to secure by Letters Patent is:

1. In a tuning scale for radio apparatus, a scale plate bearing the station names, a casing disposed behind the said plate, partitions within the said casing forming compartments corresponding to the said station names, a slide arranged behind the said scale plate and adapted to be moved along the said plate by the tuning-in means of the apparatus, a rear wall to the said casing having openings therein corresponding to the wavelength calibrations in respect of the single stations, and a light source on the said slide adapted to project light through the said openings to illuminate the name of the station which has been tuned in.

2. In a tuning scale for radio apparatus, a scale plate bearing the station names and wavelength calibrations, a casing disposed behind the said plate, partitions within the said casing forming compartments corresponding to the said station names, a slide behind the said scale plate and adapted to be moved along the said plate by the tuning-in means of the apparatus, a light source on the said slide, a rear wall to the said casing having openings therein corresponding to the wavelength calibrations permitting the light from the said light source to illuminate only the name of the tuned-in station, and light-transmitting means on the said slide to illuminate the wavelength calibration of the tuned-in station.

3. In a tuning scale for radio apparatus a scale plate bearing the station names, a casing arranged behind said scale plate and being open towards said scale plate and containing horizontal partitions within said casing forming compartments in accordance with the station names on the scale plate in horizontal direction and having openings in its wall, and movable means for illuminating said scale plate from the back of said casing through said openings in accordance with the tuning means.

4. In a tuning scale for radio apparatus, a scale plate bearing the station names, a casing

disposed behind the said plate, partitions within the said casing forming compartments corresponding to the said station names, a slide arranged behind the said scale plate and adapted to be moved along the said plate by the tuning-in means of the apparatus, a rear wall to the said casing having openings therein corresponding to the wavelength calibrations in respect of the single stations, and a light source on the said slide adapted to project light through the said openings to illuminate the name of the station which has been tuned in, said slide being all round closed and only having an opening in the form of a narrow slot towards said casing so that the light is projected through said slot onto said rear wall of said casing.

5. In a tuning scale for radio apparatus, a scale plate bearing the station names, a casing disposed behind the said plate, partitions within the said casing forming compartments corresponding to the said station names, a slide arranged behind the said scale plate and adapted to be moved along the said plate by the tuning-in means of the apparatus, a rear wall to the said casing having openings therein corresponding to the wavelength calibrations in respect of the single stations, and a light source on the said slide adapted to project light through the said openings to illuminate the name of the station which has been tuned in, said slide being all round closed and only having an opening in the form of a narrow slot towards said casing and within said slot a light transmitting material in order to project diffuse light from said slide onto the rear wall of said casing.

6. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means.

7. In a tuning scale for radio apparatus a scale plate bearing the station names, a casing arranged behind said scale plate and being open towards said scale plate and containing horizontal partitions and transverse partitions in the vertical direction within said casing forming compartments in accordance with the station names on the scale plate and having openings in its rear wall and movable means for illuminating said scale plate from the back of said casing through said openings in accordance with the tuning means.

8. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in means of the apparatus, and a source on the said slide to illuminate the said scale plate from the rear.

9. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along

- the said plate by the tuning-in means of the apparatus, and a source on the said slide to illuminate the said scale plate from the rear, said casing and said partitions being composed of a light-reflecting material.
- 5 10. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 10 means of the apparatus, and a source on the said slide to illuminate the said scale plate from the rear, said casing and said partitions being composed of a pressed artificial material.
- 10 15. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 15 means of the apparatus, and a source on the said slide to illuminate the said scale plate from the rear, said casing and said partitions being composed of a sheet-metal having a bright surface.
- 20 25. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 20 means of the apparatus, and a source on the said slide to illuminate the said scale plate from the rear, said casing and said partitions being coated in their interior with a light-reflecting 25 substance.
- 25 30. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 30 means of the apparatus, and a source on the said slide to illuminate the said scale plate from the rear, said casing and said partitions being composed of a nonmetallic material.
- 30 35. 12. In a tuning scale for radio apparatus, a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 35 means of the apparatus, and a source on the said slide to illuminate the said scale plate from the rear, said casing and said partitions being composed of a cardboard material.
- 40 45. 13. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 50 means of the apparatus, and a source on the said slide to illuminate the said scale plate from the rear, said casing and said partitions being composed of a pressed artificial material.
13. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 10 means of the apparatus, and a source on the said slide to illuminate the said scale plate from the rear, said casing and said partitions being composed of a pressed artificial material.
14. In a tuning scale for radio apparatus a scale plate bearing the station names, light-screening partitions within a casing arranged behind said plate and having openings in its rear wall, and movable means for illuminating said scale plate from the back of said casing through said openings in accordance with the tuning means, said means comprising a slide arranged behind the said scale plate and adapted to be moved along the said plate by the tuning-in 15 means of the apparatus, and a source on the said slide to illuminate the said scale plate from the rear, said casing and said partitions being composed of a pressed artificial material.
15. In a tuning scale for radio apparatus, a scale plate bearing the station names, a casing disposed behind the said plate, partitions within the said casing forming compartments corresponding to the said station names, a slide arranged behind the said scale plate and adapted to be moved along the said plate by the tuning-in 20 means of the apparatus, a rear wall to the said casing having openings therein corresponding to the wavelength calibrations in respect of the single stations, and a light source on the said slide adapted to project light through the said openings to illuminate the name of the station which has been tuned in, the said partitions being exchangeable.

HANS STRASSENBURG. 45
